STEPHEN R. COLEMAN, OF LOS ANGELES, CALIFORNIA

CHECK BOOK COVER FOLD AND FILLER

Application filed July 6, 1931. Serial No. 548,805.

This invention relates to improvements in units comprising foldable covers and pads or fillers of check blanks removably held therein characterized by novel means to fasten the fillers in the cover.

It is the primary object of this invention to provide a unit of the character described wherein a simple, economical, compact, and durable cover structure having a check pad 10 retainer and a pad of novel construction, is provided. It is another object of this invention to provide a structure of the character described having a retainer adapted to have a filler or pad laterally placed in position and 15 removed, the retainer being constructed so as to cooperate with the filler stub to properly locate the filler laterally and to effectively hold the filler in position. A further object of this invention is to provide a pad retainer 20 so constructed that the fillers therefor may be made without the usual retaining member and wire stitching, and, upon severance of the check blanks, a minimum of waste will occur at the stub which is left. A still 25 further object of this invention is to provide a cover and retainer so arranged that a register book may be removably placed within the cover, this book serving for keeping a record of the deposits and withdrawals and also as a 30 pass book. In addition to the broader objects of this invention, there are certain details of structure whereby a compact unit easily manipulated and ornate in appearance may be obtained.

These objects, together with other objects and corresponding accomplishments, are obtained by means of the embodiment of my invention illustrated in the accompanying drawings, in which:

Fig. 1 is a perspective view of the cover unfolded, exposing the check blanks, the register book not being shown; Fig. 2 is a view of a fragment of the cover showing the retainer partly in section and a fragment of the stub end of the pad fastened in position; Fig. 3 is a view similar to Fig. 2, taken in section through the retainer without the pad and the catch in open position; Fig. 4 is a side view as seen looking in the direction of the arrows 4 in Fig. 2; Figs. 5 and 6 are sections

as seen upon the lines correspondingly numbered in Fig. 2; Fig. 7 is a perspective view of the check book cover with pad and register book fastened therein; Fig. 8 is a transverse section through the structure shown in Fig. 7 in closed position; and Fig. 9 is a perspective view of a modified form of cover, pad and register book.

Referring with more particularity to Figs. 1 to 8 inclusive, a cover is shown comprising leaves 10 and 11 foldable along a median crease 12. This cover may be made of leather, leather substitute, cloth, fabric, or any other material suitable for covers of this character. The pad retainer and pad 60 are mounted upon the leaf 10 and the inventive features reside therein.

At one end of the leaf 10 is a pad retainer comprising a trifurcated flange or inner wall having a middle prong 13a and end 70 prongs 13b and 13c. The middle prong 13a is offset from the plane of prongs 13b and 13c so that leaf 10 may be inserted in the space therebetween with prong 13a on the outside and prongs 13b and 13c on the inside. The 75 prong 13a and leaf 10 may be fastened together by eyelets 14. There is a channel like portion 15 overhanging the end of leaf 10 having an outer wall 16 and a down turned lip 17. A detent 18 is upset from the inner 80 wall of the channel being cut therefrom with its severed end forming a lock shoulder to engage in a hole in the pad. Stamped and upset from the inner wall at one side of the retainer is a post 19 adapted to be disposed 85 in a slot in the stub end of the pad. At the opposite side of the retainer in the inner wall is a slot 20 and pivotally mounted on the wall at the slot is a keeper 21 having a flange 21a and a finger hold 21b. The keeper may be 90 positioned clear of the slot as shown in Fig. 3 in unlocking position or with flange 21a in the slot as shown in Fig. 2 in pad locking position. The retainer is preferably stamped from resilient metal.

The pad which is generally indicated by 22 has a perforated line 23 adjacent the stub end and so located that when the pad is in position within the retainer, the checks may be easily severed along the perforated line 23. 100

It will be noted that the pad 22 is held at its stub end between lip 17 and the inner wall of channel 15 and the lip holds the pad downwardly against the leaf 10. This makes possible the elimination of the retaining tongue commonly attached to fillers and also the wire stitching greatly reducing the cost of manufacture. The waste end of the stub is thus made small and instead of using the stub end for keeping an account of withdrawals and deposits, the register book hereinafter described may be used. The stub end of the pad or filler 22 is provided with a hole 24 to receive detent 24. At the ends are slots 25, one to receive the keeper 21 and the other post 19. It will be noted that the outer wall 16 has an offset rise from the plane of lip 17.

The pad is inserted from the side. Keeper 21 is placed in unlocking position as shown in Fig. 3. The stub end of the pad is then pushed sideways into the retainer. Due to the clearance of wall 16 of the retainer, the pad may bend upwardly to ride over detent 18, and when hole 24 registers therewith the detent slips into place and the stub end straightens. Post 19 enters the adjacent slot 25 and limits the travel of the pad. Keeper 21 is now swung to closed position as shown in Fig. 2. It will be noted that detent 18 offers a shoulder which abuts the wall of hole 24 so that the pad cannot be pulled endwise from the retainer. Post 19 and keeper 21 aid in holding the pad. Resiliency of lip 17 or the outer wall is not relied upon to hold the pad in place.

The register book 26 may have one of its covers inserted between leaf 10 and prongs 13b and 13c. These serve to clamp the book in place. The book should be of such length and thickness that when folded over as shown in Fig. 8, the bulk of the book lies below the plane of outer wall 16 enabling compact folding. Obviously, the book is easily removed and replaced.

Referring to Fig. 9, the structure shown is the same broadly as before described with the exception that an additional leaf or fold 11a is added making a trifold cover. The leaf 11a just covers the register book. The prong 13a is shown attached to the inner side of leaf 10. Other variations may be resorted to in the manner of fastening the retainer to the cover without departing from the invention.

The structure enables a single ply cover to be used such as a layer of fabricoid making the cover economical. The retainer is economical to make and easy to attach to the cover. The structure enables a considerable saving in paper and economy in manufacture.

What I claim is:

1. The combination of a cover fold, a retainer for pads comprising a channel with a flange adapted to be secured to a leaf of the

cover fold, said channel having an opposing outer wall with an end lip inset toward said inner wall to provide a clearance space between said outer and inner walls, a detent tongue upset from the inner wall with its tip facing the web of said channel; and a pad of sheets having a hole to receive said detent tongue. 70

2. The combination of a cover fold, a retainer for pads comprising a channel adapted to be secured to a leaf of the cover fold, said channel having an opposing outer wall with an end lip inset toward said inner wall to provide a clearance space between said outer and inner walls, a detent tongue upset from the inner wall with its tip facing the web of said channel, a limiting post upstanding from said inner wall adjacent a side edge, a keeper pivoted on said retainer having a flange for disposition in said slot; and a pad of sheets having slots in opposing side edges at the stub end for receiving said post and said keeper and a hole to receive said detent tongue. 75 80 85

3. The combination of a cover fold, a retainer for pads comprising a channel adapted to be secured to a leaf of the cover fold, said channel having an opposing outer wall with an end lip inset toward said inner wall to provide a clearance space between said outer and inner walls, a detent tongue upset from the inner wall with its tip facing the web of said channel, a limiting post upstanding from said inner wall adjacent a side edge, a slot in the edge of said inner wall opposite to said post, a keeper pivoted on said retainer having a flange for disposition in said slot; and a pad of sheets having slots in opposing side edges at the stub end for receiving said post and said keeper and a hole to receive said detent tongue. 90 95 100

4. The combination of a cover fold, a retainer for pads comprising a channel with a forked flange, one of the prongs thereof being secured to a leaf of the cover fold, said channel having an opposing outer wall with an end lip inset toward said inner wall to provide a clearance space between said outer and inner walls, a detent tongue upset from the inner wall with its tip facing the web of said channel, a limiting post upstanding from said inner wall adjacent a side edge, a keeper pivoted on said retainer having a flange for disposition in said slot; and a pad of sheets having slots in opposing side edges at the stub end for receiving said post and said keeper and a hole to receive said detent tongue. 110 115 120 125

In witness that I claim the foregoing I have hereunto subscribed my name this 30th day of June, 1931. 125

STEPHEN R. COLEMAN.
